UNITED STATES PATENT OFFICE.

EDWARD FIELD AND FRANCIS M. COTTON, OF LONDON, ENGLAND.

IMPROVEMENT IN STEAM-ENGINES.

Specification forming part of Letters Patent No. 146,239, dated January 6, 1874; application filed April 24, 1873.

To all whom it may concern:

Be it known that we, EDWARD FIELD and FRANCIS MICHAEL COTTON, both of London, Kingdom of Great Britain and Ireland, have invented certain Improvements in Steam-Engines, of which the following is a specification:

This invention has reference to engines of the kind known as compound high and low pressure engines, in which high-pressure steam is made to do duty first in a high-pressure cylinder, and thence passes into a second or low-pressure cylinder, wherein it expands and acts upon another piston, as well understood.

The first part of our invention relates to the construction of such engines with a combined high-pressure cylinder and low-pressure piston, which works wholly within the low-pressure cylinder, a steam-chamber being formed between the two cylinders, whence steam is supplied alternately to the respective ends of the high-pressure cylinder, and is from thence exhausted directly into the same ends of the low-pressure cylinder. The second part of our invention relates to the construction of the engine with valves carried by the combined high-pressure cylinder and low-pressure piston, for governing the communication between high and low pressure cylinders, and with other valves working in a separate valve-chamber outside of the low-pressure cylinder, for opening and closing its exhaust-ports. The third part of our invention relates to the actuating of the whole of the said valves directly by means of high-pressure steam in the respective ends of the low-pressure cylinder.

Figure 1, Sheet 1, is a longitudinal vertical section of parts of a steam-engine embodying the first, second, and third parts of our invention. Fig. 2 is a transverse section taken in the line A B of Fig. 1. Fig. 3 is a transverse section taken in the line C D of Fig. 1. Fig. 4 is a section taken in the line E F of Fig. 1. Fig. 5 is an end view of the exhaust-valve-chamber cover.

We arrange a reciprocating high-pressure cylinder or chamber, *a*, wholly within a low-pressure cylinder or chamber, *b*, with their axes parallel to each other, the two cylinders being, by preference, concentric, as shown. The high-pressure cylinder *a*, with its flanges

and covers, forms the piston of the low-pressure cylinder *b*. So it will be understood that, whenever we mention hereafter the low-pressure piston, we refer to the high-pressure cylinder, and vice versa. The piston *c* of the high-pressure cylinder *a* is fixed, and maintains a constant position relatively to the low-pressure cylinder *b*. The annular space *d* between the high and low pressure cylinders constitutes a steam-chamber, into which steam from the boiler constantly flows by the inlet *a'*, for supplying the high-pressure cylinder *a*. The admission and emission of the steam to and from the respective ends of the high-pressure cylinder are regulated by piston-valves *e* *e'*, connected together by a spindle, *e²*, and working within suitable valve-chambers *e³* *e⁴*, formed in the body or casting of the above-described combined high-pressure cylinder and low-pressure piston *a*, and furnished with suitable ports, passages, or ways, which are opened and closed, as required, by the said valves. The high-pressure cylinder *a* is arranged to communicate with the low-pressure cylinder *b* at one end by the port *f* and valve-chamber *e³*, and at the other end by the port *f'* and valve-chamber *e⁴*. The valve-chambers *e³* *e⁴* communicate with the annular steam-chamber *d* at their inner ends, and with the interior of the low-pressure cylinder *b* at their outer ends, and, with the ports *f* *f'*, form short passages or ways between the two cylinders at their respective ends, the communication being opened and closed, as required, by the movement of the piston-valves *e* *e'*. The outer face of each of these valves is wholly exposed to the action of the steam for the time being in the corresponding end of the low-pressure cylinder *b*. *n* *n'* are lugs, cast on the cylinder *a*, bored in a line with and to the same diameter as the valve-chambers, and having their inner ends closed by means of cushion-blocks *n²* *n³*, which blocks are bored to allow the valve-rod to pass through them, and, in conjunction with the lugs *n* *n'*, form steam-cushion chambers to prevent violent shock of the valves when thrown over. The ports *h* *h'*, formed in the low-pressure cylinder *b*, and governed by the piston-valves *i* *i'*, conduct the exhaust-steam from the respective ends of the low-pressure cylinder *b* into the valve-chamber *k*, whence it escapes by the ex-

haust k' . The valves $i i^1$ (like the valves $e e^1$) are exposed at their outer faces to the pressure, for the time being, in the corresponding ends of the low-pressure cylinder b , and are connected together by a spindle, i^6 , which also carries the small pistons $i^2 i^3$, operating, in conjunction with the partitions $i^4 i^5$, to cushion the exhaust-valves.

The operation of the engine is as follows: On starting the engine, its first stroke is effected by high-pressure steam entering the high-pressure cylinder a , and exerting its influence between one end of that cylinder and its fixed piston e , thereby moving the combined high-pressure cylinder and low-pressure piston a toward one end of the low-pressure cylinder b . The high-pressure steam whereby this first stroke has been effected then passes directly into the same end of the low-pressure cylinder b , and a fresh supply of high-pressure steam enters the other end of the high-pressure cylinder a , so that the combined high-pressure cylinder and low-pressure piston a is caused to perform its second or return stroke by the combined action of the expanding steam in the low-pressure cylinder b and of the high-pressure steam in the high-pressure cylinder a , thus completing the first double stroke or revolution of the engine. The subsequent strokes are effected similarly to the second or return stroke, just mentioned, by the combined action of high-pressure steam from the high-pressure cylinder a expanding into the low-pressure cylinder b , and of fresh supplies of high-pressure steam admitted into the high-pressure cylinder a at each stroke, as described, the expanded steam, after having done duty in the low-pressure cylinder b during each stroke, being exhausted therefrom or conveyed to the condenser or atmosphere during the next or return stroke.

The drawing shows the position of the parts which obtains when the low-pressure piston a has moved nearly to the end of the low-pressure cylinder b , and has thereby first closed the exhaust-port h' , and subsequently opened a communication, by the groove or channel l , between that end of the low-pressure cylinder and the steam-chamber d , thereby admitting high-pressure steam into the low-pressure cylinder, which steam has formed a cushion for the low-pressure piston a , and has thrown over the valves $e e^1$ and the exhaust-valves $i i^1$ by

acting on the faces of the valves e^1 and i^1 . The valves having been thus thrown over, the high-pressure steam which has just done duty in the cylinder a is now passing directly, by the port f' and the valve-chamber e^4 , into the end b' of the low-pressure cylinder b ; the communication between the other end of the high-pressure cylinder a and the corresponding end of the low-pressure cylinder b is closed by the valve e ; and fresh high-pressure steam is passing from the annular steam-chamber d , by the valve-chamber e^3 and port f , into the end a' of the high-pressure cylinder a for the return stroke. The port h' is closed by the valve i^1 , and the port h is open, so that the expanded steam in the low-pressure cylinder is passing, by the port h and valve-chamber k , to the exhaust k' .

The tappets $m m'$ and the prolongation i^7 of the valve-spindle i^6 are for the purpose of moving the valves by hand, in the event of their becoming set through disuse.

Our improved compound engine may obviously be made with valves differing more or less in their arrangement from those above described without departing from the distinctive character of our invention, as respects which

We claim—

1. The combination of the high-pressure cylinder a , the low-pressure cylinder b , of which the cylinder a is the piston, valves arranged and operating as described, and the steam-chamber d , surrounding the cylinder a and communicating with the steam-generator, as set forth.
2. The valves $e e^1$, working in the chambers $e^3 e^4$, carried by the combined high-pressure cylinder and low-pressure piston a , in combination with the exhaust-valves $i i^1$, working in the chamber k outside the low-pressure cylinder b , all arranged substantially as specified.
3. The combination of the cylinder b , inner sliding cylinder a , and openings provided with valves, and arranged to admit live steam to the valves at the end of each stroke, for the purpose set forth.

EDWARD FIELD.
FRANCIS M. COTTON.
